(**) Term: **14 Years**

(57) **CLAIM**

(21) Appl. No.: **29/148,510**

The ornamental design for a urine collection device, as shown and described.

(22) Filed: **Sep. 21, 2001**

DESCRIPTION

(30) **Foreign Application Priority Data**

Mar. 26, 2001 (GB) 2100623

FIG. 1 is a rear left side perspective view of the invention illustrating my design;

(51) **LOC (7) Cl.** **24-04**
(52) **U.S. Cl.** **D24/122**
(58) **Field of Search** D24/122; 4/144.1,
4/144.2, 144.3, 144.4, 114.1; 604/329, 347,
331; D7/697, 700

FIG. 2 is a left side elevation view thereof;

FIG. 3 is a top elevation view thereof; and,

FIG. 4 is a front right side perspective view thereof.

The broken line showing is for illustrative purposes only and forms no part of the claimed design.
